UNITED STATES PATENT OFFICE.

AUGUST R. RIEGER, OF CHICAGO, ILLINOIS.

SAFETY-RAZOR.

1,157,044.

Specification of Letters Patent. Patented Oct. 19, 1915.

Application filed February 17, 1915. Serial No. 8,745.

To all whom it may concern:

Be it known that I, AUGUST R. RIEGER, a citizen of the United States of America, and a resident of Chicago, in the county of Cook, 5 State of Illinois, have invented certain new and useful Improvements in Safety-Razors, of which the following is a specification.

This invention relates more particularly to that class of safety razors in which the cutting edge of the razor blade has adjustment to and from the corresponding edge of the guard shield. And the present improvement has for its various objects: To provide a simple and durable structural formation and association of parts, wherein the cutting edge of the razor blade is made adjustable to and from its guard member in an accurate and ready manner. And to provide a simple and efficient construction 10 and combination of parts whereby the razor blade is secured to the stock in a substantial yet readily detachable manner, all as will hereinafter more fully appear.

In the accompanying drawings: Figure 1, 25 is a perspective view of the present safety razor parts in an assembled condition. Fig. 2, is a like view of the stock and adjusting screw in a detached condition. Fig. 3, is a back perspective view of the stock. Figs. 4 and 5, are companion sectional elevations, 30 illustrating the parts in their respective close and wide-apart adjustment of the cutting edge of the razor blade to the guard rim of the stock.

35 Similar reference numerals indicate like parts in the several views.

Referring to the drawings, 1 represents the usual handle or stem to which the stock 2 of the safety razor is detachably secured 40 in any usual and suitable manner.

In the present improvement the stock 2 is formed of a piece or blank of resilient plate metal or the like, bent upon itself to form a rounded back 3, and a pair of flat 45 webs 4, 5, inclined toward each other and normally meeting at their free and forward ends as shown. The upper web 4 affords support for the flat razor blade 6, and to this end is provided with hook-shaped ears or 50 lugs 7 at its respective free corners, and preferably extending beyond said corners as shown. The sharp corner edges of the razor blade 6 have engagement in the recesses of the ears or lugs 7, as shown in 55 Fig. 1, and are detachably held in place by the spring finger or clip hereinafter de-

scribed. The lower web 5, aforesaid has a curved or rounded lip 5' at its free edge, to constitute the usual safety guard or shield for the cutting edge of the razor blade 6. 60

8 designates a spring finger or clip formed midway the width of the back web 3 and contiguous part of the upper web 4, of the stock, by slits in said parts, and with the free and holding end of said spring finger 65 or clip 8, extending beyond the upper web 4 for resilient engagement in a central notch 6' formed therefor in the back edge of the razor blade 6, as shown in Figs. 1, 4 and 5. With the described construction, the secure 70 holding of the razor blade is attained, and at the same time, its ready removal and replacement can be quickly and conveniently effected.

9 designates an adjusting screw disposed 75 between the resilient webs 4, 5 of the stock 1, with its inner end or point bearing against the inner inclined surfaces of said webs and adapted in a movement in one direction to force said webs apart and in a movement in 80 the other direction permit said webs to spring together. The screw 9 has adjustable bearing in the screw-threaded orifice of a bearing hub 10, carried by the curved back web 3 of the stock 1, as shown, and is preferably provided with a milled head 11 at 85 its outer end for convenient rotation by the fingers of the user.

Having thus fully described my said invention, what I claim as new and desire to 90 secure by Letters Patent, is:—

1. In a safety razor, the combination of a stock having a pair of flat webs extending in an inclined direction to each other and secured together in a resilient manner by a 95 connecting back web, the free end of one web constituting a guard and the other web having holding means for a razor blade, and an adjusting screw having bearing in the back web with its inner end adapted to bear 100 against the inclined surfaces of the pair of webs to effect an adjustment of the same, substantially as set forth.

2. In a safety razor, the combination of a stock having a pair of flat webs extending 105 in an inclined direction to each other and secured together in a resilient manner by a connecting back web, the free end of one web constituting a guard and the free end of the other web having lateral hook shaped 110 holding ears for a razor blade, a central spring finger on the back web adapted for

engagement in a notch in the back edge of a razor blade, and an adjusting screw having bearing in the back web with its inner end adapted to bear against the inclined surfaces of the pair of webs to effect an adjustment of the same, substantially as set forth.

Signed at Chicago, Illinois, this 15th day of February, 1915.

AUGUST R. RIEGER.
